UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

SNAP-SWITCH.

1,293,309.

Specification of Letters Patent.

Patented Feb. 4, 1919.

Application filed October 20, 1916. Serial No. 126,771.

To all whom it may concern:

Be it known that I, REUBEN B. BENJAMIN, a citizen of the United States, residing at Chicago, in the county of Cook and State of Illinois, have invented new and useful Improvements in Snap-Switches, of which the following is a full, clear, concise, and exact description, reference being had to the accompanying drawing, forming a part of this specification.

My invention relates to an improved snap switch in which arcing when the contact is broken is reduced to a minimum, and which will be simple in construction and efficient in use.

In the accompanying drawings, in which two embodiments of my invention are shown;

Fig. 1 is a side elevation of a key socket, parts being broken away to show the interior construction.

Fig. 2 is an axial section of part of the socket on the line 2—2 of Fig. 4.

Fig. 3 is a vertical section on the line 3—3 of Fig. 2.

Fig. 4 is an axial section on the line 4—4 of Fig. 2.

Fig. 5 is a transverse section on the line 5—5 of Fig. 2.

Fig. 6 is a transverse section on the line 6—6 of Fig. 2.

Fig. 7 is a detail end view of a ratchet sleeve.

Fig. 8 is a side elevation of Fig. 7.

Fig. 9 is a detail view of part of the key shaft.

Fig. 10 is an end view of Fig. 9.

Fig. 11 is a transverse sectional view of part of a socket, showing a modified form 40 of switch.

Fig. 12 is a detail sectional view showing the key shaft of Fig. 11.

Fig. 13 is a detail view showing the manner in which the spring contacts are secured 45 on the shaft of Fig. 12.

Referring now to the drawings in detail, my invention is shown in connection with a key socket 15 comprising the casing 16 and an insulating base 17 for supporting the shell and center contacts 18 and 19 respectively, and the snap switch mechanism 20. The socket has the usual bushing 21 for connection with a conduit, the usual fiber lining 22 for insulating the casing, and the usual

shoulder 23 for retaining the base 17 in position. The center contact 19 is held in place on the base 17 by means of a reinforcing and binding plate 24 into which is threaded the retaining screw 25 and the binding screw 26. The snap switch mechanism 20 comprises an operating key 27, an operating shaft 28 to which the key is secured, leaf spring contact members 29 actuated by the shaft 28, fixed substantially flat contacts 30 and 31 co-operating with the spring contact 29, and a combined retaining and ratchet member 32 for holding the spring contacts 29 in place on the shaft 28 and for engagement with the ratchet members on the shaft 28. The shaft 28 is rotatably mounted in 70 a bearing plate 33 secured to the base 17 (Fig. 4).

Each spring contact 29 comprises a semi-circular portion 34 which engages the shaft 28, and a bent spring contact portion 35 for 75 engagement with the contacts 30 and 31. These spring contacts 29 are exact duplicates and are formed in the same dies. The retaining and ratchet member 32 may be formed of sheet metal into a cup shape 80 (Figs. 7 and 8), provided with an opening 36 through which the shaft 28 passes and with opposed slots 37 through which the spring contact portions 35 extend. The edge of the cup portion is provided with opposite ratchet 85 teeth 38 which engage corresponding ratchet teeth 39 on the key shaft 28. The cup portion of the member 32 embraces the semi-circular portions 34 of the spring contacts and holds the spring contacts on the operating shaft 28. For holding the ratchet teeth 38 and 39 in operative position a bow spring 40 is provided, having an opening which receives a reduced portion 41 of the key shaft. This bow spring is secured to the 95 key shaft by riveting over the end of the key shaft at 42 (Fig. 6).

The fixed contact 31 is secured to the base 17 by means of a screw 43 which also assists in holding the shell contact on the base. The 100 other side of the shell contact is secured to the base by means of a screw 44 and nut 45. The contacts 30 and 31 are located in recess 46 in the base 17. This recess has opposed flat walls 47 and 48 extending at substantially right angles to the contacts 30 and 31, and is also provided with flat portions 49 and 50 which engage the tips of the bent.

spring contact portions 35 to prevent reverse rotation as indicated in dotted lines, Fig. 3. The contact 30 has a binding plate portion 51 in which is threaded a binding screw 52. 5 In operation assuming that the parts are in the position shown in full lines in Fig. 3, as the key is rotated the spring contact portion 35 is bent still more, and the frictional resistance of the parts 35 on the contacts 30 10 and 31 causes a springing of the portions 35 which retards them with respect to the shaft 38. This bending and retarding of the spring contact portions 35 continues until the tips of the portions 35 pass a plane 15 through the axis of the shaft 28 perpendicular to the contacts 30 and 31. Shortly after this the spring contact portions 35 will be released and due to their bent condition and their retardation with respect to the shaft 20 28, will snap suddenly to the position shown in dotted lines in Fig. 3, breaking the circuit suddenly and preventing arcing.

A similar action of the spring contact portions 35 takes place in their movement from 25 the dotted line position of Fig. 3 to the full line position, the portions 35 being bent or doubled up and retarded until their tips pass a plane through the axis of the shaft 28 perpendicular to the walls 47 and 48, when they 30 will be released suddenly and snap into engagement with the contacts 30 and 31. The spring contact is prevented from reverse rotation by engagement of the tips of the contact with the walls 47 and 48 and with the 35 slot portions 49 and 50.

The ratchet connection between the shaft 28 and sleeve 32 and the leaf spring 40 permits the shaft 28 to be turned backward without turning the spring contact, the projections 39 sliding up the sloping sides of 40 the teeth 38 and the spring 40 yielding to allow the necessary endwise movement of the shaft 28.

In Figs. 11, 12 and 13 another form of 45 shaft and spring contact is shown, in which the spring contact is secured directly to the shaft and the switch key is secured onto the shaft so that it unscrews from the shaft when turned in a direction opposite the direction in which the spring contact member rotates.

In this form the insulating base 17 and the bearing plate 33 may be the same as in the form of Figs. 1 to 10.

55 The shaft 53 is split at 54 to receive the leaf spring contacts 55, 55^a and the switch key 56 is screwed onto the split threaded end 57 of the shaft 53 to hold the contacts in place. If the key is turned in the wrong 60 direction, it simply unscrews from the shaft.

In this form of switch as well as in the form of Figs. 1 to 10, the tension in the leaf spring contacts may be such as to tend to hold the free ends of the spring contacts 65 separated (Fig. 13), so that when they snap

away from the fixed contact, there will be a double break in the circuit, lessening the tendency to arcing.

Having thus described my invention what I claim as new and desire to secure by Letters Patent is:—

1. A snap switch comprising a substantially flat contact, a substantially flat insulated surface in a plane substantially perpendicular to the plane of said contact, a rotatable shaft, said flat surface and said flat contact each extending on both sides of planes through the axis of said shaft perpendicular to said planes respectively and having their intersection substantially parallel to said axis, and a bent leaf spring contact carried by said shaft, having a free tip portion moved by said shaft into contact, in contact and out of contact with respect to said flat contact, and with respect to said insulated surface.

2. A snap switch comprising a substantially flat contact, a substantially flat insulated surface in a plane substantially perpendicular to the plane of said contact, a 90 rotatable shaft, said flat surface and said flat contact each extending on both sides of planes throughout the axis of said shaft perpendicular to said planes respectively and having their intersection substantially parallel to said axis, and a bent leaf spring contact carried by said shaft, having a free tip portion moved by said shaft into contact, in contact and out of contact with respect to said flat contact, and with respect to said insulated surface, said tip snapping away from said flat contact into engagement with said insulated surface shortly after it passes the plane through the axis perpendicular to the plane of the flat contact, and snapping away 95 from said insulated surface shortly after it passes the plane through said axis perpendicular to said insulated surface.

3. A snap switch comprising a rotatable shaft, two substantially flat contacts on opposite sides of said shaft, two substantially flat insulated surfaces on opposite sides of said shaft lying in planes substantially perpendicular to the planes of said contacts, said flat surfaces and said flat contacts each 110 extending on both sides of planes through the axis of said shaft perpendicular to said surfaces and contacts respectively and having their intersections substantially parallel to said axis, and a bent leaf spring contact 115 carried by said shaft having two free tip portions moved by said shaft into contact, in contact and out of contact with said flat contacts and with said insulated surfaces, said tips snapping away from said flat contacts 120 and flat surfaces respectively shortly after they pass said perpendicular planes.

4. A switch comprising a first contact, a rotatable shaft, and two superposed inner and outer bent leaf spring contact members 130

carried by said shaft, the tip of the outer one of said spring contact members being moved by said shaft into contact, in contact and out of contact with respect to said first

5 contact.

10 5. A switch comprising a first contact, a rotatable shaft, and two superposed inner and outer bent leaf spring contact members carried by said shaft, the tip of the outer one of said spring contact members being moved by said shaft into contact, in contact and out of contact with respect to said first contact, the tension in said spring members being such as to tend to hold their tips sep-

15 arated.

20 6. A switch comprising a first contact, a rotatable shaft, and two superposed inner and outer bent leaf spring contact members carried by said shaft, the tip of the outer one of said spring contact members being moved by said shaft into contact, in contact and out of contact with respect to said first contact, each spring member having a semi-circular portion embracing said shaft, and a sleeve

25 member surrounding said semi-circular portions for holding them on the shaft, said sleeve member having an opening in its side through which said leaf members extend.

30 7. A switch comprising a first contact, a rotatable shaft, and two superposed inner and outer bent leaf spring contact members carried by said shaft, the tip of the outer one of said spring contact members being moved by said shaft into contact, in contact

and out of contact with respect to said first 35 contact, each spring member having a semi-circular portion embracing said shaft, and a sleeve member surrounding said semi-circular portions for holding them on the shaft, said sleeve member having an opening in 40 its side through which said leaf members extend, said shaft and sleeve having co-operating ratchet members whereby said shaft will cause rotation of said sleeve and spring members in one direction only. 45

8. A switch comprising a first contact, a rotatable shaft, and two superposed inner and outer bent leaf spring contact members carried by said shaft, the tip of the outer one of said spring contact members being moved 50 by said shaft into contact, in contact and out of contact with respect to said first contact, each spring member having a semi-circular portion embracing said shaft, and a sleeve member surrounding said semi-circular 55 portions for holding them on the shaft, said sleeve member having an opening in its side through which said leaf members extend, said shaft and sleeve having co-operating ratchet members whereby said shaft 60 will cause rotation of said sleeve and spring members in one direction only, and a spring tending to hold said ratchet members in engagement.

In witness whereof, I have hereunto sub- 65 scribed my name.

REUBEN B. BENJAMIN.
